UNITED STATES PATENT OFFICE.

GEORGE SEMLER, OF WEST ORANGE, NEW JERSEY.

DESIGN FOR A CUSPIDOR.

SPECIFICATION forming part of Design No. 21,358, dated February 23, 1892.

Application filed January 11, 1892. Serial No. 417,739. Term of patent 14 years.

To all whom it may concern:

Be it known that I, GEORGE SEMLER, a citizen of the United States, residing at West Orange, in the county of Essex and State of New Jersey, have invented and produced a new and original Design for Cuspidors of which the following is a specification.

The accompanying drawing shows a perspective view of a cuspidor, showing my new design.

Similar letters of reference indicate corresponding parts.

The leading feature of my design consists in the funnel-shaped top of the cuspidor, which funnel-shaped top has a scalloped upper edge and representations of the petals of a flower on its upper surface.

A is the body of the cuspidor; B, the flar-

ing or funnel-shaped top. a are scallops on the upper edge of said top, and b are representations in relief of the petals of a flower on the upper surface of said top B, the said petals extending from the lower part of the top to the upper edge of the same and terminating in the scallops a.

What I claim is—

The design for a cuspidor, substantially as herein shown and described.

In testimony that I claim the foregoing as my invention I have signed my name in presence of two subscribing witnesses.

GEORGE SEMLER.

Witnesses:

PAUL GOEPEL,
CHARLES SCHROEDER.
